UNITED STATES PATENT OFFICE.

ELMER L. KENYON, OF CHICAGO, ILLINOIS.

PHONOGRAPH-HORN.

1,303,208.

Specification of Letters Patent.

Patented May 6, 1919.

Application filed February 18, 1916. Serial No. 79,022.

To all whom it may concern:

Be it known that I, ELMER LAWTON KENYON, a citizen of the United States, residing at Chicago, in the county of Cook and State 5 of Illinois, have invented certain new and useful Improvements in Phonograph-Horns, of which the following is the specification.

This invention relates to sound intensifying horns and particularly to means for 10 clarifying the tones delivered by such horns and to avoiding the confusion thereof, incident to the use of these horns as heretofore made.

As well known, horns for phonographs, or 15 for other similar purposes, are designed to increase the loudness of the tones entering the horn. This is accomplished by confining the sonorously vibrating air within the limiting walls of "horns", or so-called "resonance boxes", or "resonance chambers", thus 20 carrying the sound in one general direction, and also utilizing the well known principle of resonance. While this method is efficacious and has no counteracting disadvantages 25 where mere loudness of sound is the desideratum, as in fog horns and the like, it does introduce serious disadvantages in the reproduction of music.

A long, uninterrupted horn applied to a 30 phonograph not only kills many of the finer notes but more or less noticeably confuses the music produced thereby, because it introduces tones produced by the horn vibrating irregularly in an attempt to respond as 35 a unit to different vibrations set up in different parts of the horn by the music, and also because the horn entire is generally too unwieldy to respond at once to the changing vibrations of the music, thus in a horn of 40 ordinary length the closing vibrations in response to one note will interfere with the opening vibrations in response to another note.

It is the object of the invention to remedy 45 the defects and disadvantages above described and to produce a horn, particularly applicable for intensifying fine and delicate music, in which extraneous audible tones will be diminished and in which clash or 50 confusion of different parts of the horn at

the same time instead of producing a perfect response to the music will be rendered impossible.

I have also discovered a large amount of "blur" in rendition of fine music is due to 55 an excessive vibration at the mouth of the horn. This phenomenon may be easily understood when it is considered that all of the particles of the horn, between the two ends thereof, are constrained by particles on both 60 sides but that the end of the horn is free and unconstrained. With vibrations traveling from the inner to the outer edge of a phonograph horn, the free end or mouth vibrates with an excessive amplitude and so produces 65 a variation in the tone different from that produced by a synchronous vibration of the body of the horn and tending to "blur" the music.

It is a further object of my invention 70 therefore to prevent this excessive vibration at the end of the horn, first, by tightly binding said end to the body of the horn, or second, to weight the end of the horn, or both, whereby the particles at the end of the horn 75 will be prevented from vibrating excessively, but will have their vibrations brought into uniformity with those in the body of the horn, thus eliminating any interfering vibrations and encouraging those that improve 80 the quality of the music.

It is a still further object of the invention to suspend each section of a horn made according to my invention in such a position 85 as to interfere as little as possible with its freedom to vibrate as the music demands.

In the drawings:

Figure 1 is an elevation, partly in section, of a phonograph equipped with a horn constructed according to my invention. 90

Fig. 2 is a cross section on the line 2—2 of Fig. 1.

In the drawings, 1 represents the casing of a phonograph, the details of which are not important to the invention; 2 represents 95 the customary bracket or arm, pivotally supporting the phonograph horn by means of the carrier 3 and pivot 4 as shown. I divide a horn into a plurality of independent sections, aligned however, so that their contour 100

lies in a continuous surface. The sections are connected with each other by connecting pieces 5' of leather or other light flexible non-resonant material capable of preventing escape of sound therethrough. These sections are secured in place, for instance each is secured to the rod 5 by rigid connections 6. The space between the sections has been somewhat exaggerated in the drawing but should be appreciable. With the horn made up of sections as indicated, it will be impossible for vibrations to travel from one section to another. Extraneous tones in the various individual sections will be absent because each section is made small enough so that it can respond as a unit and completely to the vibrations set up by the music in it and will not be dampered by the lagging effect of a large volume of material integral with it, which is not responding to the same musical vibrations but is setting up inharmonious and unsympathetic vibrations of its own. If extraneous tones are present in the individual section they will be so feeble as to be inaudible. By extraneous tones are meant tones not intended in the music and resulting either from the failure of the horn as a whole to vibrate correctly or because the vibration of some region of the horn is hampered by the lagging effect of some other part of the horn not quickly enough assuming the required vibration. Of course the length and general dimensions of the sections are matters of importance inasmuch as for different kinds of music it is probable that different sections would be preferable. This, however, must be determined by actual experiment, it being obvious that there must be some length which would give the best results with each and every kind of music and one series of lengths for the different sections which would give very much better results than a solid horn for any kind of music generally played upon the phonograph.

The described constructions of the horn will not diminish the volume of sound because it does not in the least interfere with either of the two principles described at the beginning of the specification, which are responsible for increasing the volume. In so far as concerns delivering the music in the same general direction, a sectional horn arranged according to my invention is substantially as good as a solid horn. In so far as concerns resonance, the sound increasing effect in my horn will be substantially as great as that of a solid horn of the same size and shape because the resonance will be substantially the same. It is, of course, obvious that the sections may overlap, provided the passage of vibrations from one to another be prevented by padding or the like.

To eliminate or diminish the whip action, I provide at both free ends of each section,

a tight metal crimping band or cap, such as 65 illustrated in the drawings by reference character 7. This band binds the particles at the end of the horn more tightly to the body of the horn than the particles in the body of the horn are bound to the adjoining particles thus introducing a more uniform vibration of the entire section, and preventing excess vibrations or whip action at the end of the horn. It would also be possible to entirely sheath the horn or horn section in 75 metal or other material crimping this material more tightly at or adjacent the ends than it is bound to the body portion of the horn or horn section.

I claim:

1. A horn for sound intensifying, comprising a plurality of sections adapted to make an interrupted conical shaped horn when supported in line, means to support said sections with their axes in alinement, 85 and having the end periphery of each section spaced from the end periphery of the adjoining section, whereby the superficial periphery of said assembled sections will lie substantially in a cone and the individual vibrations of the sections will be permitted.

2. In apparatus of the class described, a horn comprising a plurality of sections arranged and supported in alinement, each section spaced from the preceding one and each 95 free for individual vibration and the periphery of all sections lying within a regular continuous surface.

3. In apparatus of the class described, a horn comprising a plurality of sections arranged and supported in alinement, each section spaced from the preceding one and the periphery of all sections lying within a regular continuous surface, and each intervening space between sections bridged in an 100 airtight manner but without damping the individual vibration of the sections so that the vibrations of one section shall interfere as little as possible with those adjoining.

4. A sound intensifying apparatus comprising a horn made up of a plurality of separate sections supported for free individual vibration, each whereof, is supported independently for independent vibration, but all of which are supported with their axes in 115 alinement.

5. A sound intensifying apparatus of the class described, comprising a body portion made up of a plurality of separate sections, each of said sections supported independently for independent vibration, and means for supporting said sections in spaced apart relation with their respective longitudinal central lines falling in a continuous line.

6. A sound intensifying instrument, comprising an interrupted horn made up of a plurality of separate sections each spaced from the preceding section and supported

for free individual vibration, metallic reinforcements tightly binding and weighting the ends of said sections, whereby to make the vibrations at the ends of each section 5 uniform with those of the center without preventing the vibration of the section.

In witness whereof, I hereunto subscribe

my name to this specification in the presence of two witnesses.

ELMER L. KENYON.
